BY *Victor J. Evans*
ATTORNEY

UNITED STATES PATENT OFFICE.

HERMAN H. BRUGMANN, OF SPENCER, IOWA.

STORM-SASH FASTENER.

Application filed September 4, 1925. Serial No. 54,525.

This invention relates to improvements in fastening devices and has for an object the provision of means especially designed for securing a storm or other sash within a window frame in such manner as to prevent the said fastening means from being visible at either side of the sash.

Another object of the invention is the provision of a fastening device which in addition to the above and other advantages, is simple in construction, reliable in use and may be readily and easily attached.

With the above and other objects in view, the invention further includes the following novel features and details of construction, to be hereinafter more fully described, illustrated in the accompanying drawings and pointed out in the appended claim.

In the drawings:

20 Figure 1 is an elevation illustrating the use of the invention.

Figure 2 is an enlarged fragmentary sectional view on the line 2—2 of Figure 1.

25 Figure 3 is a similar view illustrating the use of the invention in connection with a metal window frame and metal sash frame.

Referring to the drawings in detail wherein like characters of reference denote corresponding parts, the reference character 30 10 indicates a window sash within which is secured a storm sash, the frame of which is indicated at 11.

The fastening means comprises a pin 12 which is driven into the frame 11 and held 35 against accidental removal by means of barbs 13. The pin is provided with an annular flange 14 which forms a stop and limits the point at which the pin may be driven into the frame 11. The flange is spaced from 40 the outer end of the pin and this end provides a stud 15 which is designed to enter

a socket provided in the sash 10. The socket is preferably provided with a metal lining 16 to receive the stud 15.

The flange 14 is thin so that the frame 11 and sash 10 practically abut and the fastening device will not be visible from either the inside or outside of the frame.

In the use of the invention in connection with a metal window frame 10' and a metal sash frame 11', the pin 12' is provided at one end with threads to receive a nut 17 which binds the flange 14' against the outer edge of the frame 11', while the stud 15' formed by the outer end of the pin enters 55 an opening 18 provided in the window frame.

The invention is susceptible of various changes in its form, proportions and minor details of construction and the right is herein reserved to make such changes as properly fall within the scope of the appended claim.

Having described the invention what is claimed is:

In combination with a metal frame and sash, a fastening pin consisting of an elongated cylindrical body provided with an integral flange extending circumferentially around the pin and positioned thereon at a point between the ends of the body to cause long and short projecting extensions to be formed, the long projection to pass through a hollow rail of a sash frame and being terminally threaded with a holding device 75 engaging the threads to secure the long projection in said hollow sash frame, the short projection to enter a socket formed in a window frame.

In testimony whereof I affix my signature.

HERMAN H. BRUGMANN.
